DESIGN FOR A GAME BOARD

Walter Weiglin, New York, N. Y.

Application December 16, 1946, Serial No. 135,556

Term of patent 7 years

(Cl. D34—5)

To all whom it may concern:

Be it known that I, Walter Weiglin, a citizen of no country, residing at New York city, in the county of the Bronx and State of New York, have invented a new, original, and ornamental Design for a Game Board, of which the following is a specification, reference being had to the accompanying drawing, forming a part thereof.

Fig. 1 is a plan view of a game board, showing my new design.

Fig. 2 is a cross-sectional view taken on line 2—2 of Fig. 1.

I claim:

The ornamental design for a game board, substantially as shown.

WALTER WEIGLIN.
